(57) **CLAIM**

The ornamental design for a computer, as shown and described.

DESCRIPTION

FIG. 1 is a front, left, top, perspective view of a computer showing our new design;

FIG. 2 is a rear, right, top, perspective view of the computer shown in FIG. 1;

FIG. 3 is a front elevational view of the computer shown in FIG. 1;

FIG. 4 is a rear elevational view of the computer shown in FIG. 1;

FIG. 5 is a left-side elevational view of the computer shown in FIG. 1;

FIG. 6 is a right-side elevational view of the computer or shown in FIG. 1;

FIG. 7 is a top plan view of the computer shown in FIG. 1; and,

FIG. 8 is a bottom plan view of the computer shown in FIG. 1.

The broken lines and the vent holes shown in the drawings represent portions of the computer that form no part of the claimed design.
